[57] CLAIM

The ornamental design for a hand held dynamometer, substantially as shown and described.

DESCRIPTION

FIG. 1 is a front elevational view of a hand held dynamometer showing my new design;
FIG. 2 is a top plan view thereof;
FIG. 3 is a rear elevational view thereof;
FIG. 4 is a bottom plan view of FIG. 3;
FIG. 5 is a right side elevational view of FIG. 1;
FIG. 6 is a left side elevational view of FIG. 1;
FIG. 7 is a partial perspective view of another embodiment of the bearing pad of the dynamometer shown in FIG. 1; the portions of the dynamometer not shown are identical to those shown in FIGS. 1-6.

FIG. 1

FIG. 2

FIG. 3

FIG. 4

FIG. 5

FIG. 6

FIG. 7
